V. A. KREPPS.
CHECKREIN HOOK.

No. 449,045.

Patented Mar. 24, 1891.

his Atty.

UNITED STATES PATENT OFFICE.

VIRGIL A. KREPPS, OF KENSICO, NEW YORK, ASSIGNOR TO WILLIAM H. RUSHFORTH, OF RUTHERFORD, NEW JERSEY.

CHECKREIN-HOOK.

SPECIFICATION forming part of Letters Patent No. 449,045, dated March 24, 1891.

Application filed April 14, 1890. Serial No. 347,761. (No model.)

To all whom it may concern:

- Be it known that I, VIRGIL A. KREPPS, a citizen of the United States, and a resident of Kensico, in the county of Westchester and State of New York, have invented a certain new and useful Improved Checkrein-Hook, of which the following is a specification, reference being had to the accompanying drawings, forming part of the same, in which—
- 10 Figure 1 shows the device as it is ordinarily mounted. Fig. 2 is a plan view of the same. Fig. 3 is a longitudinal sectional view on line *x x*, Fig. 2, showing the hook slightly raised from normal position; and Fig. 4 is a similar 15 view on line *y y*, Fig. 2, showing the hook reversed.
- As harness is ordinarily constructed and arranged, a person must alight from the carriage in order to loosen the checkrein for any 20 purpose—for instance, to permit the animal to drink or to rest. This is sometimes inconvenient, and to accomplish the loosening of the rein without alighting and at the same time provide means for again securing said 25 rein is the main object of my invention, though I consider there is novelty in the form of the hook itself.
- It consists, first, of a plate *P*, secured to the saddle of the harness or any other suitable 30 part, or even of the vehicle, (other than at the horse's head.) Pivoted upon this plate, preferably in pillow-blocks *b*, extending upward, is a hook or pawl *p*, the tooth of which is preferably set at an obtuse angle to the other part 35 of the pawl, space being left between this longitudinal part and plate *P* for the passage of a checkrein *r*, as shown. Then, as will readily be seen, the checkrein being provided with holes *h*, it may be secured at any point desired by merely drawing the rein back until the proper hole reaches the end of the pawl, when that will drop into it and prevent movement in the opposite direction, and yet it may be released with extreme ease by drawing the 40 rein a little farther back and lifting the pawl, thus furnishing an extremely simple and effective checkrein-hook; but this is not all. To accomplish such loosening, I provide upon what may be termed the "axle" of the pawl a 45 cam or lug *c*, and upon the rein (at a point closer to the bridle end of the rein than that
- where it is desired to be held) I place another cam or lug *c'*, so located as to register with *c* when *r* is drawn backward. Now when the rein is drawn tighter lug *c'* engages with lug *c* and swings the pawl *p* over, reversing it, so that the catch-point is uppermost. This of course releases the rein and it may be permitted to slide forward as far as desired. At another point on the rein beyond the other 50 end of the holes *h*, or at such a point as will permit the rein to be loosened as much as desired, and preferably upon the opposite side of the rein, I place a third lug *c*³ and upon axle *a* a fourth lug or cam *c*⁴, so placed as to 55 register with *c*³ when *r* is drawn backward, provided the pawl *p* is reversed, as seen in Fig. 4. As *r* is drawn backward, when *c*³ strikes *c*⁴ the pawl *p* is swung backward to its normal position, as seen in Fig. 3, and is in 60 position to again engage with holes *h* when the rein is drawn back, thus again securing the checkrein in the desired position. A spring *s* is arranged to bear upon *a* to prevent the accidental misplacement of the pawl *p*. 65
- To avoid inconvenience, I run the extended checkrein back to the hand of the driver by passing it through loops formed on one of the driving-reins *R*; but it may be independent of reins *R* if preferred. 70
- The advantages of the device are manifest. At watering-troughs or in going up a hill, or when it is dark and the driver desires to loosen the checkrein to let the animal pick his own way, he need only draw upon the check-rein, 75 when the pawl is thrown over, then loosen the rein and relieve the animal, when the hook is reversed ready to again engage and hold the rein the moment the driver again draws up upon the checkrein. Again, if an animal attempts 80 to run away the driver can draw the checkrein very tight and it will hold securely, while the driver may devote his entire attention to guiding the animal or pacifying him by the use of the driving-reins. Stops of other character than holes *h* might be used—for instance, metal lugs upon the rein; but the holes are cheaper to make and more convenient. As stated, the pawl is preferably secured to the saddle of the harness, and I 85 usually construct it, as shown, with an ordinary hook above it. 90
- 95
- 100

What I claim as my invention, and desire to secure by Letters Patent, is—

A checkrein-holder consisting of a plate or support, a pawl supported upon said plate and pivoted to swing vertically, and two tripping-lugs secured to said pawl, but in different lateral and circumferential positions, in combination with a checkrein provided with one or more stops arranged to register with the engaging end of said pawl, an independent tripping-lug arranged to register with one only of the tripping-lugs connected to the pawl, and a second tripping-lug arranged to

register only with the second tripping-lug upon the pawl, said two rein-lugs being located at points differing both in lateral and longitudinal position, all substantially as and for the purpose specified.

Signed at New York, in the county of New York and State of New York, this 11th day of April, A. D. 1890.

VIRGIL A. KREPPS.
